[57] CLAIM

The ornamental design for a tissue ablation device, as shown and described.

DESCRIPTION

FIG. 1 is a isometric view of a tissue ablation device showing our new design;

FIG. 2 is a side-elevational view of the tissue ablation device shown in FIG. 1. The opposite side of the tissue ablation device corresponds to that shown in FIG. 1;

FIG. 3 is a top plan view of the tissue ablation device shown in FIG. 2;

FIG. 4 is a rear elevational view of the tissue ablation device shown in FIG. 2;

FIG. 5 is a bottom plan view of the tissue ablation device shown in FIG. 2; and,

FIG. 6 is a front elevational view of the tissue ablation device shown in FIG. 2.
